United States Patent [19]

Gamble

[11] Patent Number: Des. 285,866

[45] Date of Patent: ** Sep. 30, 1986

[54] COMBINED POCKET TOOL CASE AND KEY HOLDER

3,070,142 12/1962 McGlynn 206/37.6
3,863,477 2/1975 Klein D3/61

[75] Inventor: William L. Gamble, Unionville, Conn.

Primary Examiner—George P. Word
Attorney, Agent, or Firm—Hopgood, Calimafde, Kalil, Blaustein & Judlowe

[73] Assignee: The W. E. Bassett Company, Derby, Conn.

[57] CLAIM
The ornamental design for a combined pocket tool case and key holder, as shown and described.

[**] Term: 14 Years

DESCRIPTION

[21] Appl. No.: 592,432

FIG. 1 is a front elevational view of a combined pocket tool case and key holder showing my new design, the environmental structure shown in dotted lines being for illustrative purposes only and not a part of the design claimed;

[22] Filed: Mar. 22, 1984

FIG. 2 is a right side elevational view thereof;
FIG. 3 is a rear elevational view thereof;
FIG. 4 is a left side elevational view thereof;
FIG. 5 is a front elevational view thereof but opened up for selective removal of a key holder ring;
FIG. 6 is a bottom plan view thereof; and
FIG. 7 is a top plan view thereof.
